UNITED STATES PATENT OFFICE.

CLAUDIUS B. MOULTON, OF NORTH CAMBRIDGE, MASSACHUSETTS.

COMBINED SHAFTING-BOX AND OIL-RESERVOIR.

SPECIFICATION forming part of Letters Patent No. 292,841, dated February 5, 1884.

Application filed October 5, 1883. (No model.)

To all whom it may concern:

Be it known that I, CLAUDIO B. MOULTON, a citizen of the United States, residing at North Cambridge, in the county of Middlesex and State of Massachusetts, have invented 5 certain new and useful Improvements in Combined Shafting-Boxes and Oil-Reservoirs, of which the following is a specification.

My invention relates to an improved means 10 for preventing the dripping and escape of oil at the ends of the shafting-box and from the shaft.

The invention consists in extending the 15 ends of the shafting-box in a conical form, so that the outer reduced ends will be separated from the shaft just sufficiently to clear it—say one-sixteenth of an inch. The inner surface of the lower extended portion inclines from the outer end to the main portion, and at the 20 lower end of the inclined portion is an opening, which communicates with the oil-reservoir at the bottom of the box, and of which it forms a part, so that any used oil escaping from the box or from the shaft will be conducted to the reservoir without any waste 25 or dripping. The corresponding conically-shaped extension of the ends of the upper portion of the box forms covers, for the purpose of preventing any dirt, dust, fibrous, or other matter from falling into the lower extension or 30 basin and working into the oil-reservoir.

Referring to the accompanying drawings, Figure 1 is an elevation or side view of a shafting-box and oil-reservoir embodying my invention. Fig. 2 is a vertical horizontal section of the same. Fig. 3 is a plan view of the open lower portion of the box.

A A represent portions of shafting supported in a box, which is divided in the usual 40 manner, to form an upper and lower portion, C B. Each end of the upper and lower portions of the box is formed with a conically-shaped projection, c b, converging toward the shaft, the contracted ends being only a short 45 distance from the shaft—say one-sixteenth of an inch. The inner lower portion, b, of the extension inclines from the outer edge inwardly, forming a sort of basin, and serves to catch the used oil dropping from the shaft. The 50 ends of the main body of the box J J are curved inwardly, and converge together, as shown in Fig. 3. At the point of convergence

is an opening or passage, d, which communicates with the oil-reservoir D, as shown in Fig. 2, by means of which any oil dropping 55 from the box or shaft is directed to the opening d into the reservoir D.

A band of rubber or other material may be placed around the shaft within the extensions c b, to prevent any oil from extending out on 60 the shaft.

Connected with the lower portion, B, of the box, and of which it forms a part, is an oil receptacle or reservoir, D, having an opening in the bottom, in which is fitted a screw-plug, 65 H. A washer, h, is placed between a shoulder on the screw-plug and the bottom of the opening, to render it oil-tight. By removing the screw-plug, the reservoir D may be cleared of all extraneous matter that may settle at the 70 bottom. At the side of the lower portion, B, is an opening leading to the oil-reservoir, over which opening is a half-cup-shaped receptacle, E, into which the oil is poured, and the top of which is so arranged in relation to the 75 oil-reservoir as to indicate when the latter is filled.

F F are hollow projections on each side of the lower portion, B, by which the box is held on hangers or other suitable supports. In the 80 bottom of the lower portion, B, is an opening, in which is fitted a conically-shaped holder, I, which is open at the top and bottom, and perforated at its sides, and extends to the bottom of the oil-reservoir D. It is held in the opening at the bottom of the portion B by a rim or projection, K, on the upper end. In this holder is placed the wick, consisting of cotton waste or other fibrous material, by which the oil is fed up to the shaft, the upper end 85 of the wick being in contact with the shaft, so that as the latter rotates, the oil will be carried to every part of its bearing with the box. The inner surface of the box is provided with a lining of Babbitt metal, L, in the usual manner. The two portions of the box are secured together by bolts and the lips G. 90

The lower portion, B, of the box, together with the oil-reservoir D, the projection E, the projections F F, lips G G, and extensions b c, 100 are all cast in one piece.

What I claim as my invention is—

1. In a shafting-box, the upper and lower portions, C B, constructed with conically-

shaped converging ends *c b*, substantially as and for the purpose set forth.

2. In a shafting-box, the lower portion, *B*, constructed with the inclined ends *b b*, in combination with the guides *J J*, converging at their lower ends, the passage *d*, and the reservoir *D*, substantially as and for the purpose set forth.

In testimony whereof I have signed my name to this specification in the presence of two subscribing witnesses.

CLAUDIUS B. MOULTON.
